UNITED STATES PATENT OFFICE.

LOUIS H. WALES, OF NEW BRITAIN, CONNECTICUT, ASSIGNOR TO THE RUSSELL & ERWIN MANUFACTURING COMPANY, OF SAME PLACE.

DESIGN FOR A KNOB FACE OR CAP.

SPECIFICATION forming part of Design No. 32,620, dated May 1, 1900.

Application filed April 4, 1900. Serial No. 11,540. Term of patent 31 years.

To all whom it may concern:

Be it known that I, LOUIS H. WALES, a citizen of the United States, residing at New Britain, in the county of Hartford and State 5 of Connecticut, have invented and produced a new and original Design for Knob Faces or Caps, of which the following is a specification, reference being had to the accompanying drawings, forming part thereof.

10 Figure 1 is a front elevation of a knob face or cap, showing my design. Fig. 2 is a side elevation of the same.

As shown in the drawings, the contour of my knob-face in front view is in the form of 15 an ellipse or oval figure. At the rear edge there is a rounded shoulder or bead 3, and in front of the said bead are a second rounded

bead 4 and a parallel series of circular bead-like ornaments 5. In the center is a plane oval figure 6, slightly projecting from the 20 surrounding portion. In the space between the central oval figure 6 and the series of bead-like ornaments 5 is a series of ornaments 7, composed of scroll branches, leaflets, and flowers, all as shown. 25

Having described my invention, what I claim as new, and desire to secure by Letters Patent, is—

The design for a knob face or cap, as herein shown and described.

LOUIS H. WALES.
